MOISTENING DEVICE FOR GUMMED
CIGARETTE PAPERS

George Zint, Wapakoneta, Ohio

Application October 3, 1944, Serial No. 556,972

3 Claims. (Cl. 91—54.4)

1

The invention aims to provide a simple, inexpensive, easily operable and effective device for moistening the gummed edges of cigarette papers when rolling cigarettes with any of the conventional hand-operated cigarette-rolling machines.

Figure 1 of the accompanying drawings is a front elevation of the device.

Fig. 2 is a rear elevation.

Fig. 3 is a top plan view.

Fig. 4 is an end elevation with the actuating levers and associated parts moved to extreme positions to give access to the filling plug of the water reservoir.

Fig. 5 is a transverse section on line 5—5 of Fig. 1.

Fig. 6 is a sectional perspective view showing a portion of the reservoir.

A preferred construction has been illustrated and will be rather specifically described, with the understanding, however, that within the scope of the invention as claimed, variations may be made. It may also be stated that whereas the expressions "front" and "rear" will be herein used, it is to be understood that such expressions are relative rather than limiting.

A horizontally elongated reservoir 7 is shown, said reservoir comprising a bottom 8, end walls 9, a relatively low front wall 10, a relatively high rear wall 11, and a top 12 which extends rearwardly from the front wall 10 and terminates in spaced relation with the back wall 11. This back wall 11 rigidly carries a horizontal shelf 13 which projects rearwardly from and extends longitudinally of the upper edge of said back wall. Another wall 14 rises from the rear edge of the top 12 to a plane above the shelf 13, and the end walls 9 are provided with upward extensions 15 which are secured to the walls 11 and 14 and project upwardly from the ends of the shelf 13.

A flat wick 16 extends upwardly from the reservoir 7 between the walls 11 and 14, the upper end 17 of said wick being disposed horizontally upon the shelf 13 and projecting rearwardly beyond the rear edge of said shelf. A clamping plate 18 rests upon the horizontal upper end 17 of the wick and is secured in place by screws 19 which are threaded into openings in the shelf 13.

A pressure bar 20 is disposed under the rearwardly projecting end 17 of the wick 16 and is spaced downwardly therefrom to a sufficient extent to permit the gummed edge of a cigarette paper to be inserted between the two as shown in dotted lines at 21, in Fig. 5. The pressure bar 20 is preferably in the form of a flange on the upper edge of a bar 22. The ends of the bars 20 and

2

22 are secured to the rear ends of two levers 23 which are disposed at the outer sides of the end walls 9, said levers being fulcrumed between their ends to the extensions 15, as shown at 24. The front ends of the levers 23 are connected by a finger bar 25 which overlies the top 12 of the reservoir 7. Ascent of this finger bar and thus descent of the pressure bar 20, are limited by a nut 26 on the upper end of a stud 27 which projects upwardly from the reservoir top 12, said finger bar 25 having a slot 28 through which said stud extends. A coil spring 29 surrounds the stud 27 and presses upwardly against the finger bar 25 to normally hold the parts in such positions that proper space exists between the pressure bar 20 and the end 17 of the wick 16.

The reservoir top 12 is provided with a suitable filling plug 30. To readily gain access to this plug, the nut 26 may be removed, whereupon the levers 23 may swing to the position shown in Fig. 4, disposing the finger bar 25 in widely spaced relation with said filling plug.

When the reservoir contains a quantity of water, the wick 16 and its end 17 will remain damp. Thus, when the gummed edge of the cigarette paper 21 is interposed between the wick end 17 and the pressure bar 20, it is only necessary to depress the finger bar 25 to press the gum against the wick end 17 to moisten said gum. Depression of bar 25 will of course tilt the levers 23 to raise the pressure bar 20, and as soon as said bar 25 is released, the spring 29 returns the parts to their normal positions.

While excellent results have been obtained from the details disclosed and they may be considered as preferred, attention is again invited to the possibility of making variations within the scope of the invention as claimed.

I claim:

1. In a moistening device, a substantially rectangular reservoir to be supported on a table and formed along its entire longitudinal rear wall with an elongated substantially rectangular wick holder projecting above the flat top of the reservoir, a fixed elongated shelf projecting rearwardly from the upper edge of said holder and positioned horizontally below the upper edges of the side and front walls of said holder, a flat rectangular wick extending from said reservoir through said holder and having its upper portion resting on said shelf with its upper end projecting beyond the outer rear edge of said shelf, a rectangular clamping plate positioned between the side and front walls of said holder over the wick portion on said shelf, the rear portion of

said plate overlying the said projecting end of said wick, fastening means for securing said plate to clamp the wick on said shelf, a flat rectangular pressure bar underlying said rearwardly projecting end of the wick and spaced downwardly therefrom to permit insertion of a gummed paper between the two, two parallel levers fixedly secured at one end to the ends of said pressure bar and positioned along the outer sides of said wick holder, a finger bar fixed to the other ends of said levers and overlying the front portion of the top of said reservoir, and means for fulcruming said levers between their ends.

2. In a moistening device, a substantially rectangular reservoir to be supported on a table and formed along its entire longitudinal rear wall with an elongated substantially rectangular wick holder projecting above the flat top of the reservoir, a fixed elongated shelf projecting rearwardly from the upper edge of said holder, a flat rectangular wick extending from said reservoir through said holder and having its upper portion resting on said shelf with its upper end projecting beyond the outer rear edge of said shelf, means clamping the wick on said shelf, an open rectangular swinging frame surrounding said wick holder and including a pair of levers positioned at the outer sides of said holder and pivoted between their ends thereto, a pressure bar connecting the rear ends of said levers and underlying the projecting end of the wick and a finger bar connecting the front ends of said levers and overlying the top of the front portion of said reservoir, a threaded stud rising from the top of said reservoir and passing through an opening in said

finger bar, a coil spring on said stud beneath said finger bar and a nut threaded on said stud above said finger bar, whereby said spring will hold said pressure bar a predetermined distance from said wick until the finger bar is depressed.

3. In a moistening device, a reservoir comprising a bottom, end walls, a relatively low front wall, a relatively high back wall, and a top extending rearwardly from said front wall and terminating in spaced relation with said back wall, an elongated shelf secured to and projecting rearwardly from the upper edge of said back wall, said shelf extending longitudinally of said upper edge of said back wall, an additional wall rising from the rear edge of said top and extending to a plane above said shelf, said end walls having upward extensions which are secured to said back wall and said additional wall and project upwardly from the ends of said shelf, a wick extending from said reservoir between said back wall and said additional wall, the upper end of said wick being secured upon said shelf and projecting rearwardly beyond the same, a pressure bar underlying said rearwardly projecting end of said wick and spaced downwardly therefrom to permit insertion of a gummed paper between the two, two levers at the outer sides of said end walls and fulcrumed between their ends on said end wall extensions, the rear ends of said levers being connected to the ends of said pressure bar for raising the latter, and a finger bar connected to the front ends of said levers for operating said levers.

GEORGE ZINT.
